UNITED STATES PATENT OFFICE.

ARTHUR G. NEWMAYER, OF NEW ORLEANS, LOUISIANA.

DESIGN FOR AN IMAGE.

47,542.

Specification for Design.

Patented July 6, 1915.

Application filed April 14, 1915. Serial No. 21,474. Term of patent 7 years.

To all whom it may concern:

Be it known that I, ARTHUR G. NEWMAYER, a citizen of the United States, residing at New Orleans, in the parish of Orleans and State of Louisiana, have invented a new, original, and ornamental Design for an Image, of which the following is a specification, reference being had to the accompanying drawing, forming part thereof.

The view is a perspective view of a figure showing my new design.

I claim:—

The ornamental design for an image, as shown.

ARTHUR G. NEWMAYER.

Witnesses:

U. C. JONES,
J. W. FANZ.
